UNITED STATES PATENT OFFICE

104,712

DESIGN FOR A CENTERPIECE OR SIMILAR ARTICLE

Findley Williams, Chicago, Ill., assignor to Fostoria Glass Company, Moundsville, W. Va., a corporation of West Virginia

Application April 10, 1937, Serial No. 68,663

Term of patent 3½ years

To all whom it may concern:

Be it known that I, Findley Williams, a citizen of the United States of America and resident of Chicago, county of Cook, and State of Illinois, have invented a new, original, and ornamental Design for a Centerpiece or Similar Article, of which the following is a specification, reference being had to the accompanying drawing, forming part thereof, in which—

Figure 1 is a bottom plan view of a centerpiece or similar article, showing my new design; and Figure 2 is a vertical sectional view of the same taken on line 2—2 of Fig. 1.

I claim—

The ornamental design for a centerpiece or similar article, substantially as shown.

FINDLEY WILLIAMS.
